UNITED STATES PATENT OFFICE

GEORGE E. MURRAY, OF BATTLE CREEK, MICHIGAN, ASSIGNOR TO RAILWAY ENGINEERING EQUIPMENT COMPANY, OF CHICAGO, ILLINOIS, A CORPORATION OF ILLINOIS

LOCOMOTIVE TERMINAL

Application filed April 19, 1929. Serial No. 356,454.

This invention constitutes an improvement in that method of locomotive terminal operation, as well as locomotive terminal equipment described in U. S. Letters Patent No. 1,686,103, issued October 2, 1928, to Leland G. Plant, for improvements in and relating to locomotive terminals of the direct steaming type, and having for its purpose the operation of a locomotive terminal in a manner to perform, without the use of locomotive fires and with consequent complete elimination of smoke and gas from the engine house, all of the routine locomotive operations in and around the terminal which require the use of steam pressure in the locomotive, such as parking or holding over with maintained steam pressure, shifting from place to place, re-establishing steamed condition after washing out, testing of the popvalve or other boiler accessories, and dispatching the locomotive to its assigned duty.

More specifically, the invention relates to the provision, in the operation of such a locomotive terminal, of an improved method of and means for "floating" locomotive boilers from a direct steaming line, under sufficient steam pressure to maintain their self propelling condition while they are being held over or parked.

Heretofore, in the practice of the direct steaming system, the stationary boilers constituting the extraneous source from which steam has been supplied to the locomotives have generally been operated at pressures materially below pressures at which locomotives are normally operated, the purpose being merely to bring the locomotive to self propelling condition and to maintain it at a pressure just sufficient to permit it to move from place to place in and around the terminal, as required. But with the increasing use of this direct steaming system, the need of higher stationary boiler pressures has become important, not only as a means of speeding up the filling of boilers with water at steaming temperature and developing the necessary pressure over the water by the time the boiler is filled, but also to enable the testing of safety valves at locomotive working pressures, without the use of locomotive fires.

Stationary or extraneous boiler pressures required for the last-named purpose must be, and for efficient realization of all of the aforementioned purposes should be, substantially higher than locomotive working pressures; and the use of these higher stationary boiler pressures, in the direct steaming system, introduces a new problem, particularly during the time that such a high pressure extraneous steam supply is left open to the boilers of incoming and outgoing locomotives, for keeping up locomotion pressure, at their storage stations, without fires on the locomotives; such problem having to do mainly with the tendency of the high pressure extraneous source to overcharge the locomotive boiler and lift the safety valve, thereby causing waste of steam and developing an objectionable working environment.

The present invention meets the aforesaid problem by taking into account certain economic factors that have been gathered in the course of experience with the direct steaming system. Higher steam pressures maintained in the locomotive boiler that is being held under steam without locomotive fire, cause greater radiation heat losses from the locomotive. Opening the locomotive freely to a high pressure steam source increases the liability to overcharge through an excessive admission of steam from the extraneous source. Too free access of steam from the main to the locomotive greatly increases the difficulty of keeping up steam pressure in the extraneous boiler. And all of these conditions make for less economical direct steaming operation.

The above conditions are particularly true where the capacity of the direct steam supply boilers is limited. Under the original direct steaming practice, difficulty was often encountered in maintaining a high working pressure on the extraneous boilers, where a considerable number of locomotives were being supplied with steam during the hold-over period, because the locomotives were left free to respond immediately to fluctuations in pressure of the direct steam supply boilers. This in turn made it very difficult to re-establish full working pressure on the

direct steam supply boilers following an overload or other conditions that caused the pressure to fall. In other words, where pressures rise and fall in locomotives, which are being "floated" on the steam line from the extraneous source, in response to the rise and fall of pressures in the extraneous stationary boilers, high pressures can be gained in the extraneous boilers only at the expense 10 of unnecessarily high and wasteful pressures on the locomotive.

Another important factor gathered from experience with the direct steaming system is that when a locomotive is maintained at a 15 pressure relatively low but still high enough to provide for self propulsion in and about the terminal, the radiation losses are so far reduced that the drag on the extraneous boiler becomes economically low; and by governing the admission of steam while the locomotive boiler is "floated" from the steam line, so that there is just sufficient steam to compensate for condensation occurring at the low pressure employed in the locomotives, 25 extraneous boiler pressures may be built up rapidly and maintained at high efficiency without difficulty. While the pressure in the locomotive boiler will fall and be replaced by the extraneous source as the loss is increased 30 by radiation, pressure in the extraneous steam main will be maintained, by the recuperating capacity of the extraneous boiler, substantially constant at the high pressure needed in caring for a considerable number of incoming and outgoing locomotives at the hold-over or parking stations.

The object of the present invention is to provide suitable apparatus for and a practicable method of applying the direct steaming system in fireless locomotive terminals which, while adapted to economically and quickly establish steamed condition on locomotives appropriate for testing safety valves at locomotive working pressures and facilitating a quick get away when leaving for assigned duty, will admit of holding locomotives under steam at a substantially constant pressure or pressures within certain practical limits materially reduced from that 45 of the extraneous source during the lay-over period at the terminal, either after the locomotive has been refilled and steamed up or when brought to the storage station from the fire dumping station; and to have these conditions apply to any number of locomotives, 50 within the capacity of the terminal, standing under connection with the direct steaming high pressure source, without charging the locomotive to the point of popping; without undue drop of locomotive pressure below that 55 which is desired for fireless terminal practice; without such drain upon the extraneous boiler plant as will complicate the maintenance 60 of the latter at proper working pres-

sures; and without sacrificing the capacity of the system to quickly restore each locomotive boiler to high steaming pressure appropriate to pop-valve testing, or for accelerating departure for assigned duty, when desired.

An important factor in establishing the balance between the radiation losses or condensation in the locomotive that is being held over at low locomotion pressure and the rate of flow from the relatively high pressure and large capacity extraneous steam source, is the proper design of what is termed the connection for "floating" the locomotive boiler on the main steam line. While this is a matter that must be determined by expert knowledge, it is important that it be available to unskilled operators; hence, the invention contemplates not only introducing into the direct steaming system a new method of floating locomotive boilers from an extraneous high pressure steam source, but a novel so-called boiler floating connection to and from which the locomotive boiler may be shifted by merely selecting one or another of two appropriate valves, namely, a floating valve preadjusted to maintain the described relatively low and economical steaming pressure, and the main steaming valve adapted for use in rapidly restoring the locomotive to steamed condition after washing out its boiler, or for running up the locomotive pressure efficiently to the pressure at which its safety valves are set, when it is desired to test such valves, or to a pressure appropriate for dispatching the locomotive from the hold-over station to its assigned duty.

The present invention proceeds upon the principle of supplying, from a steam source having the capacity to maintain pressures materially higher than those required for fireless operation of terminals, to a locomotive or locomotives, steam that is caused to flow through a passage of such restricted capacity that it will transmit steam to the locomotive boiler only at a rate which will be sufficient to keep the locomotive pressure up to the relatively low degree that is commensurate with a low rate of radiation loss, and which rate of steam supply will be so low with relation to the capacity of the steam source as to permit the prompt building up or constant maintenance of steam pressure in the extraneous source.

In the preferred practice of this invention, the restricted steam supply passage bearing the described relation to extraneous boiler capacity, locomotive boiler heat losses and required fireless terminal operation will be embodied in one or more by-passes around the main valve that supplies steam at the time of refilling, so that in holding a locomotive at self propelling pressure without fire, either after dumping its fire or after it is brought to steaming pressure by the direct

steaming method before lighting its fire, it will simply be necessary to open a designated by-pass valve and leave the rate of steam flow into the locomotive entirely to the controlling influence of the by-pass in order to achieve the objects above explained.

To cite an example, in actual practice with this system, it has been found that by maintaining a steam pressure of 200 pounds in the 10 stationary supply boilers and by-passing steam from this supply through a $\frac{1}{2}$ -inch connection around the main direct steam supply valve, which is ordinarily of 2-inch size, a steam pressure of about 90 pounds can be maintained steadily in locomotive boilers of approximately 4000 gallons capacity standing in a closed enginehouse; and also it has been determined that a steam pressure of about 120 pounds can be maintained steadily in locomotive 15 boilers of 2000 gallons capacity thus supplied through the same $\frac{1}{2}$ -inch by-pass connection under the same conditions. This shows the practical importance of this relationship, since it enables the use of one by-pass of a uniform size at each locomotive storage station at a terminal, to serve as a means for holding under reduced self propelling pressure, locomotives of a considerable range in size, all supplied by steam from 20 a direct steaming main in which a relatively high constant pressure is maintained.

While it is conceivable that the present invention could be realized to a measurably advantageous degree through skillful operation of the main valve that controls the supply of steam in volume necessary to the filling operation of the boiler, as by carefully graduating a degree of opening equivalent to the restricted passageway of a by-pass, it is better to employ, and a preferred embodiment of the present invention consists in employing, the described separately controlled individual passages for these two stages of steam supply, namely, the main 35 passage, with its own individual valve, of proper capacity for supplying the volume of steam appropriate for boiler filling and initial development of steam pressure or quickly running up pressure, and a secondary or by-pass passage or passages, with individual controlling valve or valves, having a carrying capacity when the valve is wide open that admits a volume of steam just sufficient to maintain the desired reduced 40 pressure on a locomotive held thereby in floating connection with the main steam supply, so that in changing from one stage of steam supply to the other it is merely necessary to fully open and close these valves.

Aside from the greater convenience afforded by full opening or closure of these valves to effect the desired result in place of a partial or graduated opening required with the original arrangement, this original arrangement is open to the more serious objection

that restriction of steam flow by such partial opening or closure, if practiced, would cause the valve seats and disks so operated to rapidly deteriorate due to the cutting or scoring action of the steam drawn between them at high velocity. Such damage would soon cause these valves to leak and become inoperative.

In the accompanying drawings—

Figure 1 is a schematic plan of a fireless enginehouse or locomotive terminal of the direct steaming type.

Figure 2 is a plan view on a greatly enlarged scale of one of the units of the terminal, through the medium of which a locomotive may be serviced in accordance with the present invention.

Figure 3 is an elevational view of one of the servicing units, shown in Figure 2, as viewed in a plane parallel with the locomotive stall; and

Figures 4 and 5 are, respectively, a top plan and a side elevation on a still larger scale of that portion of the means shown in Figures 2 and 3 which automatically establishes a steam supply appropriate to one or the other of two stages of the servicing operation, namely, the steaming of the locomotive up to self propelling pressure, or maintenance of pressure by compensating for heat radiation during parking of the locomotive.

Referring to Figure 1, A represents a section of the roundhouse of a locomotive terminal constructed with a plurality of locomotive servicing stalls B, and C represents a series of parking or hold-over stalls at said terminal; all of these stalls being related to a conventional type of turn-table D. E represents the so-called drops or servicing apparatus at the servicing stalls B, and F represents similar drops at the hold-over stalls C. These drops may be so located in relation to the stalls that each drop is adapted to serve a stall on either side of it. As shown in the majority of the stalls illustrated, or as shown in the first two stalls, there may be one drop for service of each stall. G represents stationary boilers which are intended to have sufficient capacity to generate a volume of steam sufficient to supply locomotives occupying any or all of the stalls B and C, in accordance with the principle of operating locomotive terminals of the fireless or direct steaming type. H represents a container in which the store filling water at a temperature appropriate to the direct steaming system; I is a pump for forcing said water to the stalls; K is a known type of separator for products blown off from a locomotive boiler as a preliminary to cleaning and refilling the boiler; and L is a condenser which receives volatiles from the separator K and delivers the condensate thereof to the water reservoir H.

1 and 2 represent pipes or mains so con-

nected that they will, respectively, supply high pressure steam and filling water to the stalls; and 3 represents a blowback pipe through which may be delivered, indirectly 5 to the reservoir H, excess water accumulating in the boilers of locomotives that are held over at stations C or other stations by the proper supply of steam under the present invention which prevents drop in pressure from 10 radiation during the waiting period. Pipe 3 may also be, and in accordance with the present showing is, the standard blowoff pipe through which solids, liquid, and volatiles pass from the locomotive to the separator K 15 in the step of the servicing operation (when it has to be performed) having to do with the washing out of the boiler.

In addition to the pipes or mains referred to, the terminal may be equipped with the 20 usual pipe 4, with a drop 4a at each station, supplying water at reduced temperature for boiler washout purposes, and pipe 5, controlled by valve 5a and its handle 5b and supplying the flexible connector 5c which 25 has a locomotive stack blower connection in case the same should be needed (see Figs. 2 and 3); but these additional connections 4 and 5 have no particular bearing upon the present invention.

30 At each drop or station E, there is a branch 1a from the high pressure steam pipe 1, connected at 6 to the automatic steaming equipment 7, 7a, 8, 8a, in which, in combination with the direct steaming terminal equipment 35 in general, the present invention mainly lies; 7 being a main steam supply passage controlled by valve 7a which, when open, releases for delivery to a locomotive boiler, steam at a temperature and pressure sufficient to rapidly bring a locomotive to a desired pressure 40 and corresponding temperature, for instance, bringing the locomotive to a pressure appropriate for holding it or moving it under its own power from place to place around the 45 terminal; or in the case of a locomotive that has been held over, bringing its pressure up to a degree appropriate to the dispatching of the locomotive from the terminal, to which end the stationary high pressure steam supply 50 will be capable of supplying steam at a temperature and pressure at least equal to and preferably materially in excess of normal operating temperature and pressure of the locomotive. The high pressure steam source 55 and the connection 7, 7a are such that when the connection is opened simultaneously with the filling of the boiler, it will cause the filling water to enter the locomotive boiler at a temperature that is above the steaming tempera- 60 ture, and, upon attainment of the desired water level, will quickly thereafter develop a desired pressure for rendering the locomotive self propelling. In addition to the steam supply controlled by valve 7a, there is a by- 65 pass pipe 8 of materially less dimension than

the passage 7 controlled by valve 8a; these parts being so designed that upon closing the valve 7a and opening the valve 8a the flow of steam from the high pressure source to the locomotive boiler will be just sufficient 70 to compensate for pressure losses incident to heat radiation while the locomotive is being held over. Pipe 8, as shown, is tapped into the pipe 7 on opposite side of the valve 7a, and pipe 7 delivers past a check valve 9 into the upper end of a drop pipe 10, which is adapted to connect through flexible coupling sections 11, 12, with the filling cock of a locomotive boiler in a known manner. Valves 7a and 8a are adapted to be controlled at will, 75 respectively, by extension rod 13, having handle 13a and indicator plate 13b, and extension rod 14, having handle 14a and indicator plate 14b.

Interposed in the drop pipe 10 are means, 80 preferably in the form of a cast steel booster 15, for mixing filling water with steam and lending impetus to the filling water entering the locomotive boiler when the latter is being refilled, besides raising the temperature 85 of the filling water to a degree that will heat the boiler uniformly during the filling operation and cause the locomotive to be at steaming temperature by the time the complement of water has accumulated. Water 90 to be mixed with steam coming in through pipe 7 is supplied to the booster 15 through a pipe 16 leading from the filling water main 2, said pipe 16 being controlled by valve 16a having an operating lever 16b.

95 Also connected with the booster 15 is a pipe 17 controlled by valve 17a, operated by chain handles 17b which leads to a branch 18 leading to the blow-back line 3. The effect 100 of this is to adapt the system, upon periodic opening of the valve 17a, to blow back from the locomotive boiler sufficient water to reduce the level to the desired showing in the gauge tubes. This will generally be done 105 periodically while the locomotive is standing at the hold-over station, and is necessitated by the condensation of the compensating steam supply delivered through pipe 8 to make up for what would otherwise be a 110 drop in pressure resulting from heat lost by radiation while the locomotive is waiting to be moved. As already stated, the blow back connection 17 leading from the drop 10 with which it connects through the 115 booster 15, serves equally well for blowing off the entire contents of the locomotive boiler as a step preliminary to washing out and refilling the boiler.

120 It will be observed that the stations F are not equipped with water supply connections, but only with the connections 7 and 8 leading to high pressure steam supply main 1 and the connection 17 leading to the blow-back pipe 3.

I claim:

1. In a locomotive terminal of the direct steaming type, means for supplying steam from an extraneous source to a locomotive, including a relatively large boiler-charging passage and a relatively small pressure maintaining passage, adapted to be selectively opened and closed, for determining the flow of steam supplied to the locomotive.
2. A locomotive terminal as described in claim 1, in which the extraneous steam source is adapted to furnish steam at or above the normal working pressure of the locomotive.
3. A locomotive terminal as described in claim 1, in which the extraneous steam source is adapted to furnish steam at or above the normal working pressure of the locomotive, and the smaller of said steam passages is adapted to automatically establish delivery to the locomotive of only sufficient steam to compensate for pressure losses incident to storing the locomotive under steam without fire.
4. A locomotive terminal as described in claim 1, in which the extraneous steam source is adapted to furnish steam at or above the normal working pressure of the locomotive, and the smaller of said steam passages is adapted to automatically establish delivery to the locomotive of only sufficient steam to compensate for pressure losses incident to holding the locomotive under steam without fire and at an approximately unvarying pressure.
5. A locomotive terminal as described in claim 1, in which the extraneous steam source is adapted to furnish steam at or above the normal working pressure of the locomotive, and the smaller of said steam passages is adapted to automatically establish delivery to the locomotive of only sufficient steam to compensate for pressure losses incident to holding the locomotive under steam without fire and at an approximately unvarying pressure which is materially below that of the extraneous steam source.
6. In a locomotive terminal, the combination of a pipe adapted for attachment to a locomotive, a high pressure steam main, a flow-back main, and valve connections between said pipe and said mains; the valved connections between the pipe and the high pressure steam main including a primary passage adapted to establish approximate equalization of steam pressure between the steam main and the locomotive, and a by-passage adapted to automatically establish delivery to the locomotive of only sufficient steam to compensate for pressure losses incident to holding the locomotive under steam without fire at a relatively unvarying pressure that is materially less than that of the high pressure steam main.
7. A locomotive terminal as described in claim 6, in which the valves which control the passages between the steam main and the locomotive, when moved from closed to full open position, leave their respective passages in control of the steam flow for the purposes stated.
8. A locomotive terminal as described in claim 6, in which there is also, in control communication with said pipe, a filling water main adapted to be opened to said pipe simultaneously with the opening of the steam main thereto.
9. In the operation of locomotive terminals of the fireless or direct steaming type, the improvement which consists in supplying steam to a locomotive boiler from a stationary boiler plant steam supply, through a passage of such fixed dimensions as to restrict the flow of steam into the locomotive to a quantity just sufficient to maintain the locomotive boiler, without fire on the locomotive, at a constant steam pressure and with corresponding water temperature materially lower than the pressure and temperature at which the stationary boiler plant is operated.
10. In the operation of locomotive terminals of the fireless or direct steaming type, the improvement which consists in supplying steam to a locomotive boiler from a stationary boiler plant steam supply, through a passage of such fixed dimensions as to restrict the flow of steam into the locomotive to a quantity just sufficient to maintain the locomotive boiler, without fire on the locomotive, at a constant steam pressure and with corresponding water temperature materially lower than the pressure and temperature at which the stationary boiler plant is operated; then connecting the locomotive boiler to the same stationary steam supply through a larger passage of such fixed dimensions as to permit steam to flow into the locomotive boiler at a rate sufficient to build up locomotive boiler pressure and water temperature, without fire on the locomotive, to approximate equalization with the steam pressure and water temperature at which the stationary steam supply plant is operated.
11. In the operation of a locomotive terminal of the direct steaming type, the improvement which consists in first discharging fire from a locomotive, then moving the locomotive under its residual steam to a parking position, supplying at such parking station, to the locomotive boiler below its water line, steam from a high pressure stationary boiler plant through a passage of such fixed dimensions that the flow of steam into the locomotive boiler is just sufficient to maintain the locomotive boiler at a relatively constant pressure and corresponding water temperature which are substantially lower than the pressure and temperature at which the stationary boiler plant is operated, holding the locomotive during a desired period with its boiler at such pressure and temperature, then

supplying steam from the stationary boiler plant to the locomotive boiler through an enlarged steam passage until the pressure of the locomotive boiler and corresponding water temperature have been boosted to a degree appropriate to rendering the locomotive self propelling without fire thereon, and then moving the locomotive to a station at which its fire is ignited and dispatching it for service.

12. In the operation of locomotive terminals of the direct steaming type, the improvement which consists in first discharging the fire from a locomotive, then moving the locomotive under its residual steam to a parking position, there discharging the contents of the boiler and utilizing the volatiles thereof for heating filling water, filling the locomotive with such heated water together with live steam from an extraneous stationary boiler plant until steam pressure, corresponding water temperature, and water level have been built up in the locomotive boiler sufficient for holding the locomotive at a relatively constant pressure that is materially below that of the extraneous boiler plant, holding the locomotive with its boiler at such steam pressure, water temperature, and water level for a desired period, then supplying the locomotive boiler with steam from the extraneous plant until its boiler pressure and water temperature have been boosted to a degree appropriate for rendering the locomotive self propelling without fire, then moving the locomotive from the storage station by its own steam energy to a fire lighting position, and there lighting the fire and dispatching the locomotive for service.

Signed at Chicago, Illinois, this 10th day
of April, 1929.
